United States Patent Office.

WALTER HASLAM, OF NEW BRITAIN, CONNECTICUT.

Letters Patent No. 77,611, dated May 5, 1868.

IMPROVEMENT IN SEAMING-MACHINES.

The Schedule referred to in these Letters Patent and making part of the same.

TO ALL WHOM IT MAY CONCERN:

Be it known that I, WALTER HASLAM, of New Britain, county of Hartford, and State of Connecticut, have invented certain new and useful Improvements in Seaming-Machines for uniting the edges of knitted fabrics; and to enable others skilled in the art to make and use the same, I will proceed to describe my invention, making reference to the accompanying drawings, in which like letters indicate like parts in each of the figures.

In the seaming-machines now in use for the above-stated purpose, the bed to which the leads or jacks, (which sustain the loop-supporting points or hooks) are secured, is screwed directly and permanently to the frame of the machine, and with no intention of removal, except when repairs are needed. When, however, the bed or plate is thus secured, and which may be deemed, for all practical purposes of seaming, as permanent a mode of attachment as if the frame of the machine and the bed were cast in one piece, the capacity of the machine is quite limited, and for the following reasons:

Even with skilled operatives much time is necessarily consumed in attaching to the whole range of points or hooks, the loops of the two selvedges of a fabric, inasmuch as it is important that not a loop be missed on either selvedge.

When the bed-plate of these points is attached, as above stated, or in any similar manner, to the machine, the whole operation of the seaming-mechanism must cease, both during the period when a piece of fabric is being attached prior to seaming, and also during the period when it is being detached to make room for another piece.

This loss of time and labor is so serious a matter as to require some half dozen expensive machines, and factory-room to receive them, where one machine could do their whole work, if a "set-up" fabric, all ready for seaming, could be applied to the machine the moment the preceding piece has been finished; and to effect which is the object of my invention, which consists in securing, upon the frame of the seaming-machine, stout brackets, to receive and bear up the cloth-holding plate which is to fit closely therein; in providing a stop, to insure the placing of the plate in its true position, so that the seaming-mechanism may properly perform its duty relatively to the loops of the suspended fabric; and a notch and thumb-screw, or their equivalents, to permit the instant locking of the plate when placed in the machine, and also its prompt release whenever it is to be removed and another one, previously supplied with fabric, substituted for it.

In the accompanying drawings—

Figure 1 is a top view of the device.

Figure 2 is a front view of the same.

Figure 3 is an end view.

a is the bed or portion of a seaming-machine.

b are points, upon which the loops of the fabric are arranged for being connected by the action of the machine. These points are secured in the jacks or leads *c*, in the usual way.

The jacks or leads *c* are secured to the plate *d* by screws in a fixed position.

e e are brackets, secured firmly to the front plate of the machine, and they are so shaped as to receive and form a guiding-space, *f*, to receive, hold, and guide the plate *d* into its proper place and position for the action of the machine, and yet allow of its ready removal therefrom by the mere act of lifting.

g is a stop, against which one end of the plate or point-bar *d* strikes, to bring the points *b* accurately to their proper or relative position in the machine.

h is a slit formed in the lower edge of the plate *d*, which drops down astride of the fastener or thumb-screw *i*, by means of which screw, or its equivalent device, the plates *d* are quickly and firmly secured to or released from the machine.

Now, it will be clearly seen that by providing a suitable holding-device, for holding the plate or point-bars *d*, one, or any desired number of point-bars may be successively and quickly introduced into and removed from the machine, so as to keep the machine almost in continuous operation, thereby accomplishing in a given time, with one machine, what, in the ordinary way, would require nearly or quite six machines; and also needing the

attention of but one experienced person at the machine, whilst inexperienced or ordinary workmen or attendants can prepare the work in readiness for the machine, and as rapidly as may be desired.

It will also be seen that this plate or point-bar *d* may be held in various ways other than by a thumb-screw, as by a thumb-catch, when desirable.

I have thus endeavored to show the nature, construction, and advantage derived from this improvement, so as to enable others skilled in the art to make and use the same.

I do not claim securing the plate *d* fixedly and permanently to the front plate or bed of a machine, by means of wood-screws, for I am aware that that has already been done; but

I claim the combination, with the brackets *e* and stop *g*, of the slotted plate *d*, provided with its loop-holding points, and a thumb-screw, for the ready tightening and releasing of the plate, substantially as and for the purpose set forth.

WALTER HASLAM. [L. S.].
